(57) **CLAIM**

The ornamental design for a card applique, as shown and described.

DESCRIPTION

FIG. 1 is a top view of a first embodiment of a card applique showing our new design;

FIG. 2 is a bottom view of the card applique of FIG. 1; FIG. 3 is a perspective view of the card applique of FIG. 1 applied to a credit card, debit card, or similar card;

FIG. 4 is a top view of a second embodiment of a card applique;

FIG. 5 is a bottom view of the card applique of FIG. 4; and, FIG. 6 is a perspective view of the card applique of FIG. 4 applied to a credit card, debit card, or similar card.

The broken line showing of portions of the card applique is included for the purpose of illustrating environmental structure and forms no part of the claimed design.

The card applique has not appreciable thickness.
